UNITED STATES PATENT OFFICE.

VICTOR H. NICKERSON, OF COTUIT, MASSACHUSETTS.

DRIVE-WELL POINT AND STRAINER.

Application filed February 20, 1922. Serial No. 537,829.

To all whom it may concern:

Be it known that I, VICTOR H. NICKERSON, a citizen of the United States, residing at Cotuit, in the county of Barnstable and State 5 of Massachusetts, have invented certain new and useful Improvements in Drive-Well Points and Strainers; and I do declare the following to be a full, clear, and exact description of the invention, such as will enable others skilled in the art to which it 10 pertains to make and use the same.

This invention relates to an improved drive well point and strainer, and it has for one of its objects to generally improve upon 15 devices of this class by producing one of extreme simplicity and durability wherein the construction is such that the parts are not liable to become disarranged during the driving operation.

More specifically speaking, it is the principal object of the invention to provide a device of this class embodying among other details, an apertured tubular casing in which a wire mesh strainer is located, together with 20 means between the strainer and casing for absorbing shocks to which the strainer is subjected.

Other objects and advantages of the invention will be apparent during the course 25 of the following description.

In the accompanying drawings forming a part of this specification and in which like numerals are employed to designate like parts throughout the same:

Figure 1 is a central vertical sectional view, with parts in elevation, through a drive well point and strainer constructed in accordance with this invention.

Figure 2 is a view like Figure 1 showing 40 the novel details in section.

Figure 3 is an elevational view of one of the tubular anchoring members.

Figure 4 is a top plan view of the anchoring member shown in Figure 3.

Figure 5 is a vertical sectional view of 45 said member.

Figure 6 is a transverse section taken on the line 6—6 of Fig. 2.

Referring to the drawings in detail, the 50 numeral 1 designates a tubular casing formed with a plurality of closely spaced apertures for passage of the fluid. Arranged inside of this casing and having its ends terminating short of the ends of the latter is 55 a comparatively fine wire mesh tubular strainer 2. It may be conveniently stated

here that experience has taught that during the driving of a well with a device of this class, the strainer is subjected to severe shocks and it is desirable to eliminate this 60 as much as possible. Consequently, in the spaces between the ends of the strainer and corresponding ends of the casing, I provide novel shock absorbing means. The shock absorbing means in its preferred form comprises ring-like cushions 3 formed of elastic material, these being secured inside of the casing in any suitable way in a position to permit the opposite or adjacent ends of the strainer to abut them as clearly shown 65 in Fig. 2. The preferred means for securing these cushions in place comprises a pair of tubular anchoring members 4 and 5 respectively, the first named of which is located at the upper end of the casing and formed at 70 its outer end with a flaring flange 6 engaging the inner wall of the casing as shown. The inner end of this member projects into the strainer and one of the aforesaid cushions surrounds the same. To maintain the cushion 75 in proper position on the member, the latter is equipped intermediate its ends with shoulders which are preferably in the form of a plurality of closely spaced tongues 7 struck outwardly therefrom. Although it is 80 not essential, the lower tubular anchor 5 is preferably integral with the point 8 and it is likewise provided intermediate its ends with struck-out tongues 7 providing the shoulders against which the lower cushion 85 rests. It is of course understood that these tubular anchoring members are permanently secured to the casing 1 by any suitable means 90 to prevent displacement thereof.

In a device constructed in accordance with the foregoing description, it will be seen that during the driving of a well, the shock to which the strainer is usually subjected, will be absorbed by the rubber or resilient cushions at the opposite ends thereof with 95 which it abuts.

By carefully considering the description in connection with the drawings, persons familiar with devices of this class will doubtless be able to obtain a clear understanding of the invention. Therefore, a more lengthy and detailed description is 100 deemed unnecessary.

Since probably the best results may be 110 obtained with the construction and arrangement herein shown and described, this is taken as the preferred embodiment of the

invention. However, I wish it to be understood that minor changes coming within the scope of the invention as claimed may be resorted to if desired.

5 I claim:

1. A device of the class described including a tubular apertured casing, a strainer located therein, and shock absorbing means between the strainer and the casing.

10 2. A device of the class described comprising a tubular apertured casing, a cushion arranged inside of the casing adjacent one of the ends thereof, and a strainer also located in said casing and having one of its 15 ends engaged with said cushion.

3. A device of the class described comprising a tubular apertured casing, yieldable ring-like cushions secured therein, and a strainer also located in said casing and 20 having its opposite ends arranged in abutting relation with said cushion.

4. A drive well point and strainer comprising a tubular apertured casing, anchoring members telescoping into the opposite 25 ends of said casing and carrying elastic

cushions, and a strainer located in said casing and having its opposite ends abutting said cushion.

5. A drive well point and strainer comprising a tubular apertured casing, tubular 30 anchoring members telescoping into the opposite ends of said casing and rigidly secured thereto, being provided intermediate their ends with shoulders, a strainer arranged in said casing, the anchoring members having their inner ends telescoping 35 into said strainer, and ring-like cushions surrounding said anchoring members and interposed between said shoulders and the adjacent ends of said strainer.

6. A device of the class described including a tubular anchoring member having a plurality of spring tongues struck out therefrom intermediate its ends to form shoulders, and a ring-like cushion surrounding 45 said member and engaging said shoulders.

In testimony whereof I have hereunto set my hand.

VICTOR H. NICKERSON.
